UNITED STATES PATENT OFFICE.

BENJAMIN JOSEPH LESSARD, OF TORONTO, ONTARIO, CANADA, ASSIGNOR
OF ONE-HALF TO THOMAS PILLOW, OF SAME PLACE.

DESIGN FOR A DUST-BRUSH.

SPECIFICATION forming part of Design No. 20,006, dated July 8, 1890.

Application filed May 29, 1890. Serial No. 353,664. Term of patent 14 years.

To all whom it may concern:

Be it known that I, BENJAMIN JOSEPH LESSARD, brush-maker, of the city of Toronto, in the county of York, in the Province of Ontario, Canada, have invented a new and original Design for Dust-Brushes; and I hereby declare the following to be a full, clear, and exact description of the same.

In the drawings, Figure 1 is an elevation of my improved brush, showing the major axis of the head *a a*. Fig. 2 is an elevation showing the minor axis of the head *b b*. Fig. 3 is a plan view showing oval shape of the head.

Like letters of reference refer to like parts through the specification and drawings.

The leading feature of my design consists in an oval-shaped head *A* in connection with

a handle *C*, having a series of oval-shaped enlargements *c c*. It will be readily seen that if the head of the brush is in the form of an oval the bristles will also be arranged in the same form.

Having thus fully described my invention, what I claim as new, and desire to secure by Letters Patent, is—

The design for a dust-brush herein shown and described, consisting of the oval-shaped head *A* and the handle *C*, provided with a series of oval enlargements *c c*, as set forth.

Toronto, May 23, 1890.

BENJAMIN JOSEPH LESSARD.

In presence of—

CHARLES H. RECHE,
GUSTAVE A. PRIEST.
